FREQUENCY VARIATION RESPONSE
CIRCUITSStuart W. Seeley, Bayside, Flushing, N. Y., assign-
or to Radio Corporation of America, a corpora-
tion of Delaware

Application October 17, 1935, Serial No. 45,413

18 Claims. (Cl. 250—20)

My present invention relates to high frequency variation response circuits, and more particularly to frequency response networks of a type utilizing changes in phase relations of primary and secondary circuit voltages which occur in coupled tuned circuits when the applied high frequency energy departs from resonance with the tuned circuits.

In the past frequency variation response circuits have been proposed for many uses. Such uses have involved the indication of frequency departure from a predetermined frequency value; the maintenance of a resonant circuit at a frequency of a predetermined magnitude; or the utilization of signal energy in a receiver for automatically tuning a resonant circuit to a predetermined frequency. Such proposed circuits have usually employed frequency discriminator networks embodying resonant circuits mistuned by equal frequency values to opposite sides of a predetermined operating frequency. The direct current component of the rectified output of a discriminator network is utilized, in such prior proposed circuits, to perform the functions referred to above. One of the chief disadvantages of such prior discriminator networks has been the difficulty in aligning the mistuned circuits of the discriminator with the resonant circuits of the receiving system which are tuned to the operating frequency.

Accordingly, it may be stated that it is one of the primary objects of my present invention to provide a high frequency variation response network wherein there is not employed side circuits tuned above and below a predetermined center frequency, but wherein the frequency discriminating circuits are tuned to the common operating frequency of the entire system with the result that the aligning of such a discriminator network with other circuits of the receiving system is greatly simplified, and signaling systems embodying such discriminator networks are rendered highly practical.

The aforementioned proposals of the prior art have all substantially utilized mistuned circuits in the discriminator network in such a manner that the differential direct current output of the mistuned circuits was obtained by virtue of alternate operation of rectifiers coupled to the mistuned circuits. That is to say, in such prior circuits each mistuned circuit of the discriminator network is connected to a rectifier, and as the applied frequency departs from resonance with the desired operating frequency, the center frequency of the mistuned circuits, either one

or the other of the mistuned rectifiers becomes operative to derive a direct current from the applied signal energy.

It is, then, one of the important objects of my present invention to provide a frequency variation response network which functions in an entirely different manner from such prior proposed circuits, and wherein there is established in the frequency response network a predetermined phase difference between a primary and secondary potential of a tuned network embodying primary and secondary circuits, the phase angle between the primary and secondary potentials varying as the applied energy varies in frequency from resonance.

Another important object of the present invention is to provide a method of, and apparatus for, obtaining differential direct current potentials, or currents, whose magnitude and polarity are determined by the amount and the sign, respectively, of the difference between an applied frequency and a certain fictitious frequency, and wherein the action depends upon the fact that a 90° phase difference exists between the primary and secondary potentials of a double tuned transformer when energy of the resonant frequency is applied, and that this phase angle varies as the applied frequency varies.

An additional object of the invention is to provide a frequency discriminator network wherein the primary and secondary voltages of a double tuned transformer, which voltages differ 90° in phase when energy of the resonant frequency is applied, are added vectorially whereby the absolute magnitude of the resultant vector will be greater on one side of resonance than on the other.

Still another object of the invention is to provide a discriminator network utilizing primary and secondary resonant circuits tuned to a common operating frequency, and wherein the primary and secondary circuits are so related that two vector sum potentials of the primary and secondary voltages may be realized, one maximizing above and one maximizing below the center frequency, which latter frequency is the common resonant frequency of the primary and secondary circuits, and rectifiers being utilized to rectify those sum voltages in such a manner that the resulting direct current voltages are added in opposition; thus the sum of the direct current voltages will be zero at resonance, and the sum will be some real value whose polarity will depend upon the sign of the frequency departure when the applied frequency departs from resonance.

Still other objects of the invention are to utilize the frequency variation response network of the present invention in the demodulator stage of a system adapted to receive amplitude-modulated, or frequency-modulated, carrier waves, and wherein the demodulator networks are not only adapted to produce voltages corresponding to the modulation voltages, but also produce direct current voltages to regulate the gain of carrier wave amplifiers, and the frequency of the local oscillator of the receiving system, when the latter is of the superheterodyne type.

Still other objects of the invention are to improve generally the simplicity and efficiency of high frequency variation response networks, and more especially to provide such networks in a simple and economical manner which will not only be reliable in operation, but readily manufactured and assembled in desired signaling systems.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 schematically shows a circuit arrangement for analyzing the fundamental principle underlying the invention.

Fig. 2 illustrates a frequency discriminator network embodying a practical form of the invention.

Fig. 3 graphically illustrates the mode of operation of the arrangement in Fig. 2.

Fig. 4 is a circuit diagram of a superheterodyne receiver embodying the invention.

Fig. 5 is a modification of the demodulator network of the receiver of Fig. 4 when employed to receive frequency-modulated carrier waves.

Fig. 6 shows still another application of the present invention.

Referring now to the accompanying drawings, wherein like reference characters in the different figures designate similar circuit elements, there is shown in Fig. 1 a circuit arrangement for analyzing, and visually indicating, the fundamental principle underlying the present invention. As stated heretofore, the functioning of the present invention depends upon a predetermined phase relationship which exists between the potentials of coupled tuned circuits. In particular, the action depends upon the fact that when a pair of resonant circuits are coupled, and each circuit is tuned to the same operating frequency, then a 90° phase difference exists between the potentials across the coupled circuits. As a result the phase angle between these potentials varies as the frequency of the energy applied to the coupled circuits departs from resonance therewith.

In Fig. 1 there is shown a pair of coupled resonant circuits P and S; the circuit P is tuned to a desired frequency by shunt condenser 1, while circuit S is tuned to the same frequency by condenser 2. The high frequency waves which are to be applied to the double tuned network P-S are derived from a source 3 of high frequency waves; and the source may be, for example, a signal generator capable of generating waves having a frequency of about 465 k. c. Such a source includes a device enabling it to be adjusted

in frequency so that the frequency of the waves can be varied; and those skilled in the art are fully aware of such devices. An amplifier 4 is used to amplify the waves from source 3 prior to impression upon circuit P. The numeral 5 designates an oscilloscope of a well known type; the deflector plates being denoted by numeral 6, and the fluorescent screen thereof bearing numeral 7.

To visually depict the relations between the voltages across primary and secondary circuits P and S off and on resonance with the impressed waves from source 3, a pair of the plates 6 are connected across circuit P, while the other pair of plates 6 are connected across circuit S. Assume, now, that each of circuits P and S is tuned to a predetermined frequency of source 3, say 465 k. c., and waves of that frequency are impressed on amplifier 4 by source 3. A circular pattern 8 will form on the screen 7. This circle was observed to increase, or decrease, in diameter as the amplitude of the waves from source 3 increased, or decreased, respectively. Again, as the frequency of the waves generated by source 3 varied, the shape of pattern 8 was observed to change. The dotted ellipse 8' denotes the appearance of the pattern 25 shape when the frequency of the impressed waves is varied. The degree of coupling between P and S determines whether or not the major axis of the ellipse will exceed the diameter of circle 8. Thus, if the coupling is adjusted to critical value, 30 or over, the major axis will be greater as the applied frequency departs from resonance.

It will, therefore, be seen that the shape of the pattern on the screen 7 is dependent on the phase relations of the voltages applied to plates 35 6 by circuits P and S. Changes in amplitude off, or on, resonance only varies the size of the pattern. Further, a change of impressed frequency off resonance with circuits P and S will result in an appreciable change in the form of the pattern 8. These relations are readily understood when it is realized that a 90° phase difference exists between the potentials of circuits P and S when energy of the resonant frequency is applied, and that this phase angle varies as the 45 applied frequency varies. The oscilloscope 5, then, demonstrates in a visual manner the effect of the applied frequency on the phase relation between the potentials across P and S, and proves that for applied frequencies other than 50 the resonant frequency of circuits P-S the voltages across these two circuits are not in time quadrature.

If, now, the primary and secondary voltages are added vectorially the absolute magnitude of 55 the resultant vector will be greater on one side of resonance than on the other side. This vector sum can be physically realized, by way of example, if the circuits P and S are connected in tandem, applying the input potentials to one circuit, and taking the output off across both circuits in series. In this manner an action similar to that of a side circuit is produced even though the primary and secondary are both tuned to the center frequency.

A more suitable manner of realizing the vector sum of the primary and secondary voltages is shown in Fig. 2. The primary tuned circuit is designated by numeral 10, and is connected in the plate circuit of an amplifier 11. A source 12 of high frequency waves is connected to impress such waves on the input electrodes of amplifier 11. The secondary tuned circuit 13 is resonated to the frequency of circuit 10. The high alternating potential side of circuit 10 is 75

connected through condenser 16 to a center tap on coil 14 of circuit 13, the coil 14 and coil 15 being magnetically coupled. The condenser 16 merely serves to isolate the direct current plate potential (from source B) of the primary circuit, and its reactance is small enough to be disregarded as far as the frequency of operation is concerned.

The potentials at either end of the winding 14 with respect to the center tap thereon are 180° out of phase. Hence if the center tap, rather than one end, of the secondary circuit 13 is connected to the primary circuit 10, two potentials will be realized. One of these potentials E_2 maximizes above the center frequency f_c (the resonant frequency of both circuits 10 and 13); the other potential E_1 maximizing below the center frequency. This is graphically represented in Fig. 3, wherein the relations, in scalar magnitudes, between E_1 , E_2 and frequency are shown in solid line curves.

If a transformer, such as 15-14, is connected in the manner shown in Fig. 2, and the frequency of the waves from source 12 is equal to 25 f_c , then the two resulting output potentials will be equal in magnitude. If these potentials E_1 and E_2 are applied to two, separate, like detectors, or rectifiers, 17 and 18, and the resulting direct current voltages (or direct currents) are 30 added in opposition, the sum will be equal to zero. The output load comprises resistors 19 and 20, of like magnitude, connected in series between the cathodes of the diode rectifiers, a condenser 21, of low impedance at the operating 35 frequency, being connected in shunt with the load resistors. The junction of resistors 19 and 20 is connected to the center tap on the coil 14 through a radio frequency choke 22. Condenser 23, in shunt with resistor 20, acts with coil 40 22 to decrease the effect of the resistors on the Q value of the primary; the symbol Q being equal to

$$\frac{2\pi f L}{R}$$

45 If the frequency of the waves applied from source 12 departs from resonance, that is the resonant frequency of each of circuits 10 and 13, the sum of the rectified outputs of these two circuits combined in opposition will be some real 50 value whose polarity will depend upon the sign of the frequency departure. The dotted line curve in Fig. 3 designates the difference in scalar magnitudes of the potentials E_1 and E_2 , assuming the latter are rectified and added in opposition. It will be observed from Fig. 3 that at the resonant frequency of the primary and secondary circuits the differential voltage is zero, whereas for an applied frequency off resonance, the differential voltage increases in magnitude, and its polarity is dependent upon the sign of the frequency departure.

55 In general, the rate of change in scalar magnitude of a given resultant of two vectors at 90°, with small changes in the angle between those vectors, is greatest when the scalar value of one vector is equal to the scalar value of the resultant divided by $\sqrt{3}$, or when the ratio of vector lengths is equal to the $\sqrt{2}$. If a double tuned transformer 60 has a secondary of twice the inductance of the primary, the Q of the primary is equal to that of the secondary (when in circuit) and the coupling between circuits is critical; the primary voltage will be related to one half the secondary voltage 65 on resonance in such manner as to fulfill the

above conditions. This does not mean that a larger secondary with the same primary, or a different value of coupling, would not give a greater number of volts per cycle change in the primary plus one half the secondary sum, but in such event 5 the resultant itself would be greater. Circuit, or other, requirements might necessitate an exceedingly low tuned primary impedance; in which case a much higher ratio would be in order.

It will thus be seen that there is shown in Fig. 2 10 an embodiment of the present invention, where in there is obtained differential direct current potentials (or currents) whose magnitude and polarity are determined by the amount and the sign, respectively, of the difference between an 15 applied frequency and a certain fictitious frequency. With regard to the sensitivity of the frequency variation response network shown in Fig. 2, a measure of the sensitivity may be the developed direct current volts, or amperes, per 20 cycle of frequency deviation, per volt applied to the grid of the tube 11 whose plate circuit contains the primary 15. Regardless of the type of 25 detectors employed this quantity will be a function of the rate of change, with frequency, of the difference between the magnitudes of the input 30 potentials to the two detectors 17 and 18, or the slope of curve E_1-E_2 (Fig. 3). If these magnitudes are plotted against frequency difference (both positive and negative), the curves will intersect on the zero abscissa-ordinate with slopes equal but opposite in sign, as shown in Fig. 3.

The slope of the curve representing their difference is, therefore, equal to twice the slope at the center frequency, of the curve of input potentials to one of the detectors. This establishes the significance of a factor which will be termed S which equals two times the first derivative with respect to frequency, at resonance, of an expression for absolute magnitude of input 40 potential to one of the detectors. S is the slope of the curve E_1-E_2 in Fig. 3. It is pointed out that the value of the ordinate at the point of intersection of the two curves E_1 and E_2 becomes significant only when detectors other than those 45 with linear characteristics are used. From theoretical considerations it can be shown that S is independent of frequency, and that among other things it is a function of the secondary to primary inductance ratio, as well as the ratio between 50 actual and critical couplings between primary and secondary. Further, it can be demonstrated that the optimum value of coupling will be less than critical for any ratio of secondary to primary inductance. The sensitivity of the network can be made very great. For example, with proper constants and with 1 volt from source 12 applied, it is possible to secure an unbalance of 1.13 volts at the detector input points if the frequency departs from resonance (456 k. c.) 60 by 10 cycles. While a sensitivity of this order may not in general be necessary or desirable, this example illustrates the order of sensitivities which may be obtained if the need arises.

There has heretofore been considered the slope 65 at resonance only. The slope becomes equal to zero at two points on the curve. These correspond to two frequencies, one above and one below the resonant frequency f_c , and at these points the difference between applied potentials 70 to the two detectors is maximum. With various circuit constants, and with the coupling adjusted to give a maximum slope at resonance, these maxima will normally appear at positive and negative values corresponding to frequencies 75

which are sufficiently well separated to give adequate operating range for most circuit applications of the response network. This is particularly true if the range of frequencies applied to the network is limited by the selectivity of preceding circuits.

If it becomes necessary to increase the frequency separation of the two maxima it may be done by either increasing the value of coupling above the optimum, or by decreasing the Q of the circuits. Either method will decrease the factor S at the center frequency, although an increase in coupling will cause the least change in sensitivity for a given increase in separation. If square law detectors are used, their outputs will be proportional to the square of the scalar magnitudes of the applied potentials. It can be shown that if square law detectors are used, the optimum coupling is independent of the ratio between secondary and primary inductances, and is equal to 0.578 times critical coupling.

The response network shown in Fig. 2 shows one specific manner for combining the direct current output potentials, or currents, of the rectifiers 17 and 18 to produce the differential effect. It is to be clearly understood, however, that detectors of the plate rectification type may be used instead of the rectifiers shown. In that case a differential winding would be placed between the two plates of the detector tubes; and the magnetic field of the differential winding will then be zero at resonance, and in opposite directions on the two sides. Thus, detected output currents would be added in opposition. The response network of Fig. 2 is capable of many circuit applications. The diodes 17 and 18 need not be separate tubes, but may be disposed within a common tube envelope, as in the 6H6 type tube. Where the waves from source 12 are modulated carrier frequencies, the condenser 21 not only has a low impedance at the operating frequency, but, in general, it is desirable that it be low at useful modulating frequencies.

The resistances of the series resistors 19 and 20 may be between 0.5 and 1.0 megohm, and it is further pointed out that the radio frequency choke coil 22 is optional. However, if this choke coil is used, then it is desirable that the condenser 23 be used. If the resonant, or center, frequency is applied to the grid of the amplifier tube 11, the voltages E_2 and E_1 will be equal. These voltages are rectified by the diodes 17 and 18, and direct currents will flow into resistors 19 and 20 in opposite directions with respect to ground. Thus, the net direct current potential produced by the two voltage drops between the cathode side of resistor 19 and ground is equal to zero.

If, however, the applied frequency departs from resonance the potentials across the diodes will be unequal in magnitude. As a result unequal voltage drops will be produced in the resistors 19 and 20 and a direct current potential will exist across both resistors, the polarity of which net direct current potential will depend upon the sign of the frequency departure.

The network of Fig. 2 is capable of many uses. Fig. 4 illustrates one such use wherein a superheterodyne receiver utilizes the response network for a triple function. The received signals are demodulated; automatic volume control (AVC) voltage is provided from the demodulated signals; and automatic local oscillator frequency control (AFC) voltage is also derived from the demodulated signals. The receiver is of a con-

ventional type adapted to receive amplitude-modulated carrier waves; for example, those in the broadcast range of 550 to 1500 k. c. The receiver may comprise the usual signal collector A followed by a tunable signal amplifier 30. The amplified signals are fed to a first detector 31 which has a tunable input circuit 32, local oscillations being impressed on the detector 31 by a local oscillator. The latter may be of any desired type; it is shown as comprising a triode 33, 10 of the 6F7 type, which has a tunable circuit 34 connected between its control grid and cathode. Direct current blocking condenser 35 is connected between the high alternating potential side of circuit 34 and the grid, while a grid leak resistor 36 is 15 connected between the grid and cathode.

The rotors of the variable tuning condensers of the amplifier 30, first detector 31 and oscillator 33 are mechanically coupled for uni-control tuning adjustment. The plate of tube 33 is reactively coupled, as at M, to the circuit 34 to produce local oscillations. Any well known method of transmitting the local oscillations to the mixer, or first detector, 31 may be used. For example, the oscillations may be impressed upon the 25 cathode of the detector 31 through coupling M₁. The plate circuit of the mixer tube includes circuit 37 which is tuned to the operating I. F., for example 465 k. c. Any well known device may be 30 electrically associated with the local oscillator to maintain the oscillator tuning "tracking" properly so as to keep the I. F. value constant over the receiver tuning range. Such a device, for example, comprises condensers in series and shunt with the oscillator tuning condenser, and the 35 condensers being properly chosen for the required function.

The I. F. energy in circuit 37 is amplified through amplifier 38 containing one, or more, 40 amplifier tubes; the input circuit 39 being coupled to circuit 37 and being tuned to the operating I. F. The amplified I. F. energy is impressed upon the network including the two rectifiers. This network is constructed substantially the same as that shown in Fig. 2. For this reason 45 corresponding elements will be designated by the same numerals, but differentiated by prime notations. Thus, the primary circuit 10' is tuned to the I. F. of 465 k. c., and is magnetically coupled to the secondary tuned circuit 13', tuned to the 50 same I. F. The high alternating potential side of the circuit 15' is connected through blocking condenser 16' to the midpoint of coil 14'.

The condenser 21' has a low impedance at the operating I. F., and in general it is desirable that 55 it be low at useful modulating frequencies. As shown the junction of resistors 19' and 20' is connected to ground through condenser 23', and the audio and AVC voltages are taken off at this point. The junction point 40 is connected to the 60 subsequent audio utilization network through an audio coupling reactance 41. The AVC voltage is impressed on the stages whose gain is to be regulated by a lead 42. The latter is connected to the signal grid circuits of the amplifier 30, 65 mixer 31 and I. F. amplifier 38 through pulsating current filter resistors 43. Those skilled in the art are fully aware of the manner of operating of the AVC circuit; this acts to regulate the gain of the controlled tubes in a sense to maintain the carrier amplitude at the circuit 13' substantially uniform despite carrier amplitude variations at collector A.

The differential direct current potential for the AFC function is taken from the cathode side of 75

resistor 19'. The lead 44 is connected, through filter resistor 45, from the cathode side of resistor 19' to the grid 46 of the frequency control tube 47. The latter may be a pentode of the 5 6F7 type and is then the pentode section of the tube whose triode section is oscillator 33. The plate 48 is connected by lead 50 to the high alternating potential side of circuit 34. Direct current potential of proper magnitude is supplied 10 to the plate 48 from a positive potential source +B. Direct current blocking condenser 51 is connected in series with the coil 34' of circuit 34. The bleeder 47' is connected between +B and ground. The cathodes of oscillator 33 and tube 15 47 are connected to a tap 48' on bleeder 47'. The initial bias for grid 46 is provided by the bleeder section 49', a high frequency by-pass condenser 50' being shunted across section 49'.

The resistor 53 may have a magnitude of the 20 order of 20,000 ohms, and condenser 52 may have a value of 0.0002 mfd. The grid 46 of tube 47 is connected to the junction of resistor 53 and condenser 52 through condenser 54.

Considering the operation of the system shown 25 in Fig. 4, it is first pointed out that the audio voltage component of the detected I. F. current is taken off at point 40, because at resonance, when receiving amplitude-modulated carrier waves, the audio, as well as direct current, voltages across 30 resistors 19' and 20' will be equal and opposed. Hence, at I. F. resonance there will be no audio potentials between point 40' and ground. As far as audio components are concerned the system acts exactly as though point 40' were grounded 35 with the outputs of the two diodes 17' and 18' acting in parallel. Therefore, the point 40, at the junction of resistors 19' and 20', is a potent source of audio voltage to supply the following 40 stages of audio amplification followed by a reproducer), and no other audio detector is necessary.

The direct current voltage taken off between 45 point 40' and ground has the proper polarity for AVC action. This potential will bear the same ratio to the developed audio voltages as is found in the conventional diode detector AVC system. The fact that it maximizes at one side of resonance is of no significance if the AFC network 50 is used. When the AFC is cut out of circuit, as by manual control 60, the point 40' is grounded, and this will cause the direct potential at point 40 to maximize on resonance. If it is necessary to maximize the A. C.—D. C. impedance ratio it 55 can be seen that the D. C. impedance is equal to one half the resistance of one of the series resistors, even though the resistors are not in parallel as far as direct currents are concerned.

The use of a normally active control element 60 in an automatically controlled frequency system will not permit the carrier to depart sufficiently far from resonance to hazard the above facts. Incidentally, it is to be noted that the "translation" gain of the rectifier network (audio output 65 divided by I. F. input) will be greater than with conventional circuits since the primary and one half secondary voltages are added (vectorially), but that the selectivity will approximate that of the primary circuit 10' alone.

70 The direct current voltages taken off from between 40' and ground are equal and opposed at I. F. resonance. However, and as illustrated in Fig. 3, when the energy applied to circuit 10' is of a frequency off resonance AFC voltage will 75 be applied to the control grid 46 of control tube

47. The connections between the plate circuit of tube 47 and oscillator circuit 34 are such that a negative capacity is reflected across the oscillator circuit.

It can be seen that the resistor 53 and condenser 52 are in series across the oscillator tuned circuit. If the resistance of 53 is large compared to the reactance of the condenser 52, currents through this series circuit will be substantially in phase with the voltage across the oscillator tuned circuit. This current passing through the condenser 52 produces a voltage across condenser 52 which lags the voltage across the oscillator tuned circuit by substantially 90°. This voltage is applied to the grid of the control tube 47 which is preferably of the high $m\mu$, high plate impedance type. It can then be seen that the plate current flowing in connection 50 to tube 47 will be substantially 90° ahead of the voltage across the oscillator tuned circuit. The current through 20 the tuning condenser of the oscillator tuned circuit lags the voltage across that circuit about 90°. Thus, any plate current flowing in connection 50 to tube 47 acts as though the current flowing in the variable tuning condenser had been 25 decreased.

In other words, the tube 47 produces a negative capacity effect on the oscillator circuit. The magnitude of this negative capacity is, of course, a function of the mutual conductance of tube 47. 30 Thus, if the AFC voltage applied to the grid of tube 47 is positive thereby overcoming some of the bias applied in the cathode circuit of that tube, its mutual conductance is increased. The amount of leading current flowing in connection 35 50 is thereby increased, which is the same as though the lagging current flowing through the variable tuning condenser had been decreased. This in turn acts as though that condenser had been decreased in value thereby causing the tuned 40 frequency to increase.

Assuming, now, that a signal impressed on primary circuit 10' is approaching the I. F. value of 465 k. c., but is less than the latter, and that point 40' will have a positive potential with respect to ground. The frequency departure may be due to a shift in oscillator frequency towards a lower frequency, or due to tuning the receiver towards the high end of the tuning range. Thus, the grid 46 becomes positive, and increases the 50 gain of tube 47. This will result in an increase in the negative capacity reflected across oscillator circuit 34; and the frequency of the oscillator circuit will increase. Thus, the frequency difference between the signal and oscillator circuits will automatically be made to increase, and approach, towards the desired I. F. value. The reverse is true of the case where the signal energy applied to circuit 10' is departing from I. F., and becoming greater in magnitude. The AFC action 55 will commence as soon as a little of the side band energy of a modulated carrier wave is applied to the primary circuit 10'.

It can be seen that if the applied frequency is, for example, lower than the resonant frequency, the absolute magnitude of the alternating potentials applied to one of the diodes will be greater than those applied to the other diode. If the coil 14' of the secondary circuit 13' were reversed in its connection to the diodes, the diode 65 formerly receiving the greater potential would now receive the lesser potential. The polarity of the differential direct current voltage is then reversed from the former case. It will, therefore, be seen that the polarity of point 40' can be 70 75

made either positive or negative when the given off-resonant frequency is applied. It is apparent that interchanging the diode connections at the ends of coil 14' produces the same result as reversing the phase of the coupling between coils 15' and 14'. Accordingly, it will be seen that the polarity of the direct current voltage produced at point 40', when a given off-resonant frequency is applied, depends on the phase of the coupling between coils 15' and 14'. In the circuit shown in Fig. 4 the coupling between the coils 14' and 15' is phased so that point 40' becomes positive with respect to ground when the applied signal is lower than the resonant frequency.

15 It is a relatively simple matter to service an AFC system of the type shown in Fig. 4. Those skilled in the art are fully aware of the relative ease of aligning circuits 10' and 13' with the other I. F. circuits 37 and 38. Of course, the receiver 20 may be of a type using a combined oscillator-first detector network in place of independent circuits. In such a case, a pentagrid converter tube is used, as is well known.

Further, the frequency control circuit actuated by the AFC voltage may be replaced by other types of networks which will accomplish the desired results. For example, networks disclosed by C. Travis in application Serial No. 19,563, filed May 3, 1935 may be used. Again, if the choke 22' 30 and condenser 23' are not used, a choke must be included in any external connection to the point 40.

The receiving system shown in Fig. 4 can be employed to receive frequency-modulated carrier waves. That is to say, the frequency variation response network shown embodied in the system of Fig. 4 can be utilized in connection with detecting frequency modulated waves. In Fig. 5 there is only shown, in order to preserve simplicity 40 of disclosure, the portion of the response network between the primary circuit 10' and the audio frequency network. It will be observed that the networks are substantially similar except for the following changes. In the first place the condenser 21', when receiving frequency modulated waves, is given a magnitude which is sufficiently small to by-pass energy of intermediate frequency, but is small enough not to shunt the audio frequency currents. Furthermore, the 50 condenser 23' is replaced by condenser 23'', and the latter is connected in shunt with resistor 19'. Lastly, the audio voltage component of the rectified intermediate frequency energy is taken off from point 40', instead of from point 40 as shown 55 in Fig. 4.

In every other respect the circuit arrangement may be exactly as that shown in Fig. 4. The detection network in Fig. 5 will result in AVC voltage which is taken off at point 40; 60 AFC voltage which is taken off at point 40'; and audio voltage which is also taken off at point 40'. In the case of a receiver of frequency-modulated waves the AFC network will be of particular advantage since it is especially desirable in such 65 reception to keep the oscillator circuit resonant to that frequency which will result in the operating I. F. when a desired station is tuned in. However, it will be observed that detection of the frequency-modulated waves is accomplished without 70 the utilization of mistuned rectifier circuits, which are tuned to opposite sides of the operating carrier frequency, a method which has been employed heretofore. In the present detection arrangement of frequency-modulated waves the primary 75 circuit 10' is tuned to the same carrier frequency

as the secondary circuit 13', and the audio voltage at point 40' varies in polarity and magnitude in dependence upon the frequency departure corresponding to the modulation applied to the carrier wave.

Another use for the frequency variation response network shown herein is illustrated in Fig. 6. In this figure, there is shown a circuit arrangement for indicating in a visual manner when the carrier of a transmitter departs from its predetermined operating frequency. Conventional, and well understood, circuit networks are conventionally represented in the circuit arrangement of Fig. 6. The numeral 68 represents the transmitter oscillator which may be considered as operating, for example, at 1000 k. c. The usual monitoring oscillator operates at a frequency of 1,000.5 k. c.

Those skilled in the art are fully aware of the method employed for monitoring transmitter oscillators so as to maintain them at the frequency of 1000 k. c. In order to indicate to the transmitting station operator when the oscillator frequency shifts, there is employed the arrangement of Fig. 6. In this arrangement the monitoring 20 and transmitter oscillator energies are fed to a detector 61, and there is filtered out from the detected output the 500 cycle energy resulting from the detection process. The numeral 62 designates any desired type of filter network which 25 can pass energy of 500 cycles. The 500 cycle energy is impressed upon the frequency response network which comprises the primary winding 63, which is coupled as shown to the secondary winding. The primary and secondary windings may 30 be of the iron core type, and are tuned to the 500 cycle frequency. The diode rectifier 65 has its anode connected to the high potential side of the secondary winding, and the cathode of rectifier 65 is connected to the low potential side of the 35 secondary winding through a series path which includes resistor 66, resistor 67 and the cathode to anode space current path of diode rectifier 65. An alternating current by-pass condenser 68 is connected in shunt with resistors 66 and 67, and 40 the visual indicating device 70 is connected in shunt with condenser 68. Condenser 63' prevents resistor 67 from being short circuited. The 45 condenser 63' could be placed, if desired, between ground and the low potential side of resistor 67.

The indicator 70 may be an ammeter which is properly calibrated to indicate departures as low as 0.1 cycle off the 500 cycle input energy. It is possible to generate a voltage of 10 volts across the meter 70 to indicate a one cycle variation. It 50 will be recognized that this indicating network is very sensitive, particularly at the frequency variations which are required in transmitter practice.

While I have indicated and described several 55 systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a frequency variation response network, a primary resonant circuit connected to a source 70 of high frequency waves, said circuit being tuned to a desired frequency, a secondary resonant circuit including a coil tuned to the same frequency, means for reactively coupling said circuits, means for connecting the high alternating potential side 75

of the primary circuit to the midpoint of the coil of the secondary circuit, means for rectifying the potentials at the two ends of the secondary circuit coil with respect to the low potential side of the primary circuit and means for adding the resulting direct current voltages in opposition.

2. In a radio receiving system, a primary resonant circuit tuned to a desired operating signal frequency, a secondary resonant circuit tuned to the same operating frequency, said primary and secondary circuits being reactively coupled, connections between the primary and secondary circuits such that two alternating current potentials of like polarity exist between the ends of the secondary circuit and the low potential end of the primary, one of said potentials maximizing above the operating frequency, and one maximizing below the latter, means for rectifying the two potentials, means for adding the resulting direct current voltages in opposition, means for deriving from said last-named means a voltage corresponding to the modulation of the received waves, and another voltage varying in magnitude with the wave amplitude.

25. 3. In a radio receiver of the superheterodyne type and which employs a local oscillator, a rectifier network comprising reactively coupled primary and secondary circuits tuned to the operating intermediate frequency, means for rectifying the alternating current output of the secondary circuit, connections between the primary and secondary circuits such that the rectified signal potentials have a magnitude and polarity determined by the amount and the sign of the difference between the frequency of the coupled circuits and the frequency of the applied signal energy, and means for utilizing the differential direct current potential of the rectified signal currents for automatically regulating the frequency of the local oscillator.

40. 4. In combination with a source of modulated high frequency energy having a predetermined carrier frequency, a frequency response network comprising a primary circuit which is tuned to the said carrier frequency, a secondary circuit including a coil tuned to the same carrier frequency, said primary and secondary circuits being reactively coupled, means for connecting the high alternating potential side of the primary circuit to the mid-point of the secondary circuit coil whereby two alternating current potentials of like polarity exist between the opposite sides of the secondary circuit and the low potential sides of the primary circuit, one of said alternating potentials maximizing above said carrier frequency, and the other maximizing below the latter frequency, a path connecting the opposite sides of said secondary circuit, said path including a pair of diode rectifiers and a resistor connecting the cathodes of the diodes, means for connecting the mid-point of said resistor to said mid-point on the secondary circuit coil, and means for maintaining the low alternating potential side of said primary circuit at the same fixed potential as one side of said resistor.

45. 5. In combination, in a superheterodyne receiver of the type including a first detector, local oscillator and an intermediate frequency amplifier, at least two resonant circuits each including a coil coupled to each other and arranged in cascade, the first of said circuits being coupled to said amplifier to receive energy of intermediate frequency therefrom, each of said resonant circuits being tuned to the operating intermediate frequency, means for reactively coupling said cir-

cuits, the high alternating potential side of said first circuit being coupled to the mid-point of the second resonant circuit coil, means for rectifying the alternating potentials of like polarity at the two ends of said second resonant circuit with respect to the low potential side of the first circuit, means for adding the resulting direct current voltages in opposition, means electrically associated with the local oscillator for determining the frequency thereof, and additional means operatively associated with said rectifying means and said frequency determining means for applying said resultant direct current voltage to the frequency determining means in response to a variation in the frequency magnitude of said intermediate frequency energy.

6. In combination, in a superheterodyne receiver of the type including a first detector, local oscillator and an intermediate frequency amplifier, at least two resonant circuits each including a coil coupled to each other and arranged in cascade, the first of said circuits being coupled to said amplifier to receive energy of intermediate frequency therefrom, each of said resonant circuits being tuned to the operating intermediate frequency, means for reactively coupling said circuits, the high alternating potential side of said first circuit being coupled to the mid-point of the second resonant circuit coil, means for rectifying the alternating potentials of like polarity at the two ends of said second resonant circuit with respect to the low potential side of the first circuit, means for adding the resulting direct current voltages in opposition, means electrically associated with the local oscillator for determining the frequency thereof, additional means operatively associated with said rectifying means and said frequency determining means for applying said resultant direct current voltage to the frequency determining means in response to a variation in the frequency magnitude of said intermediate frequency energy, and means for utilizing the modulation component of the rectified potential.

7. In combination, in a superheterodyne receiver of the type including a first detector, local oscillator and an intermediate frequency amplifier, at least two resonant circuits coupled to each other and arranged in cascade, the first of said circuits being coupled to said amplifier to receive energy of intermediate frequency therefrom, each of said resonant circuits being tuned to the operating intermediate frequency, means for reactively coupling said circuits, the high alternating potential side of said first circuit being coupled to the mid-point of the second resonant circuit, means for rectifying the potentials at the two ends of said second resonant circuit with respect to the low potential end of the first circuit, means for adding the resulting direct current voltages in opposition, means electrically associated with the local oscillator for determining the frequency thereof, and additional means operatively associated with said rectifying means and said frequency determining means for applying said resultant direct current voltage to the frequency determining means in response to a variation in the frequency magnitude of said intermediate frequency energy.

8. In combination, in a superheterodyne receiver of the type including a first detector, local oscillator and an intermediate frequency amplifier, at least two resonant circuits each including a coil coupled to each other and arranged in cascade, the first of said circuits being coupled to said amplifier to receive energy of intermediate frequency therefrom, each of said resonant circuits being tuned to the operating intermediate frequency, means for reactively coupling said cir-

75. 8. In combination with a source of high frequency, means for reactively coupling said cir-

- frequency oscillations of a predetermined frequency, a second source differing therefrom by a predetermined frequency amount, means for detecting the difference frequency of the oscillations from said two sources, a primary circuit, tuned to said difference frequency, coupled to the output of said detector, a secondary circuit, tuned to said difference frequency, reactively coupled to said primary circuit, the potentials across said coupled primary and secondary circuits differing 90° in phase when energy of said difference frequency is impressed on the primary circuit, and means, responsive to a phase angle change solely between said potentials when the high frequency energy applied to the primary circuit departs from resonance with said coupled circuits, for varying the frequency of one of said sources in a sense to correct said departure.
9. In a superheterodyne receiver adapted to receive frequency-modulated carrier waves, and which receiver includes, in addition to a first detector, local oscillator network including a frequency determining element, intermediate frequency amplifier and audio frequency transmission network, a detection network comprising a primary circuit, tuned to the intermediate frequency, coupled to the output of the intermediate frequency amplifier, a secondary circuit, tuned to the intermediate frequency, reactively coupled to said primary circuit, a path of low impedance to the intermediate frequency energy connected between the high alternating potential side of said primary circuit and the mid-point of the secondary circuit, a diode rectifier having its anode connected to one side of said secondary circuit, a second diode rectifier having its anode connected to the other side of said secondary circuit, a resistive impedance connected in series between the cathodes of said two diodes, means for connecting the mid-point of said resistive impedance to said first named mid-point, an audio frequency transmission path connected to one side of said resistive impedance, the opposite side of said impedance being at a relatively fixed potential, means for applying the direct current potential developed across the entire resistive impedance to said frequency determining element in said local oscillator network for automatically varying the frequency of the oscillator when the energy impressed on said primary circuit departs from said intermediate frequency value.
10. In a superheterodyne receiver which includes a local oscillator tube having a tunable oscillation circuit, means for heterodyning the local oscillations with an incoming signal for producing energy of a predetermined intermediate frequency, means for deriving a direct current voltage from said intermediate frequency energy, when the frequency of the intermediate energy departs from the predetermined value, an electron discharge tube having its space current path connected in shunt across said tunable oscillation circuit, an electrode in the space current path of said last named tube connected to have said derived direct current voltage impressed on it, a reactive path, including a resistor in series with a condenser, connected in shunt with said space current path and said tunable oscillation circuit, and means for impressing the alternating current potential developed across said reactive path condenser upon the electrode disposed in said space current path whereby variation of the direct current voltage of said electrode will result in a variation of the

effective reactance in said tunable oscillation circuit.

11. In combination with a resonant circuit tuned to a desired wave frequency, a second resonant circuit tuned to the same frequency, said circuits being reactively coupled, a source of waves coupled to the first circuit, a pair of diode rectifiers, one of the diodes having its anode connected to a point of high alternating potential on the second circuit, the other diode having its anode connected to a point of relatively low alternating potential on the second circuit, a resistive impedance connecting the cathodes of said diodes, means establishing a point of said second circuit intermediate said two points at the potential of the high alternating potential side of the first circuit, means establishing an intermediate point of said impedance at said first intermediate point potential, and means for utilizing direct current voltage developed across said impedance by the rectification action of the diodes.

12. In combination with a first circuit tuned to a desired frequency, a second circuit tuned to the same frequency, said circuits being reactively coupled, a source of alternating current coupled to the first circuit, a pair of diode rectifiers, one of the diodes having its anode connected to a point of high alternating potential on the second circuit, the other diode having its anode connected to a point of relatively low alternating potential on the second circuit, a resistive impedance connecting the cathodes of said diodes, means establishing a point of said second circuit intermediate said two points at the potential of the high alternating potential side of the first circuit, means establishing an intermediate point of said impedance at said first intermediate point potential, and a visual current indicator means for utilizing direct current voltage developed across said impedance by the rectification action of the diodes.

13. In a superheterodyne receiver of the type provided with a local oscillator having a tank circuit tuned to a desired frequency, a network utilizing oscillations from the oscillator and producing a beat frequency, a first resonant circuit tuned to the beat frequency, a second resonant circuit tuned to the same beat frequency, said beat circuits being reactively coupled, a pair of diode rectifiers, one of the diodes having its anode connected to a point of high alternating potential on the second circuit, the other diode having its anode connected to a point of relatively low alternating potential on the second circuit, a resistive impedance connecting the cathodes of said diodes, means establishing a point of said second circuit intermediate said two points at the potential of the high alternating potential side of the first circuit, means establishing an intermediate point of said impedance at said first intermediate point potential, and means, responsive to the direct current voltage developed across said impedance by the rectification action of the diodes, for automatically adjusting the tank circuit frequency.

14. In combination with a first circuit tuned to a desired intermediate frequency, a second circuit tuned to the same frequency, said circuits being reactively coupled, a source of intermediate frequency energy coupled to the first circuit, a pair of diode rectifiers, one of the diodes having its anode connected to a point of high alternating potential on the second circuit, the other diodes having its anode connected to a point

of relatively low alternating potential on the second circuit, a resistor connecting the cathodes of said diodes, means including a condenser establishing a point of said second circuit intermediate 5 point and one end of said impedance.

5. In combination with a resonant circuit diate said two points at the potential of the high alternating potential side of the first circuit, a condenser of low impedance to intermediate frequency current connected in shunt with said impedance, means establishing an intermediate 10 point of said impedance at said first intermediate point potential, and means for utilizing direct current voltage developed across said impedance by the rectification action of the diodes.

15. In combination with a resonant circuit 15 tuned to a desired wave frequency, a second resonant circuit tuned to the same frequency, said circuits being reactively coupled, a source of waves including an amplifier coupled to the first circuit, a pair of diode rectifiers, one of the 20 diodes having its anode connected to a point of high alternating potential on the second circuit, the other diode having its anode connected to a point of relatively low alternating potential on the second circuit, a pair of series resistors of 25 equal value connecting the cathodes of said diodes, means establishing a point of said second circuit intermediate said two points at the potential of the high alternating potential side of the first circuit, means establishing the junction 30 point of said resistors at said first intermediate point potential, and means for utilizing direct current voltage developed across said resistors by the rectification action of the diodes.

16. In combination with a first circuit transmitting waves of a desired frequency, a second circuit tuned to the said frequency, said circuits being reactively coupled, a source of waves coupled to the first circuit, a pair of diode rectifiers, one of the diodes having its anode connected to 35 a point of high alternating potential on the second circuit, the other diode having its anode connected to a point of relatively low alternating potential on the second circuit, a resistive impedance connecting the cathodes of said diodes, means establishing a point of said second circuit intermediate said two points at the potential of the high alternating potential side of the first circuit, means establishing an intermediate point 40 of said impedance at said first intermediate point potential, means for utilizing direct current voltage developed across the entire imped- 45

5. In combination with a resonant circuit 5 tuned to a desired wave frequency, a second resonant circuit tuned to the same frequency, said circuits being reactively coupled, a source of waves coupled to the first circuit, a pair of diode rectifiers, one of the diodes having its anode connected to a point of high alternating potential on the second circuit, the other diode having its anode connected to a point of relatively low alternating potential on the second circuit, a resistive impedance connecting the cathodes of said diodes, means establishing a point of said second circuit intermediate said two points at the potential of the high alternating potential side of the first circuit, means establishing an intermediate point of said impedance at said first intermediate point potential, means for utilizing direct current voltage developed across said impedance by the rectification action of the diodes.

17. In combination with a resonant circuit 10 tuned to a desired wave frequency, a second resonant circuit tuned to the same frequency, said circuits being reactively coupled, a source of waves coupled to the first circuit, a pair of diode rectifiers, one of the diodes having its anode connected to a point of high alternating potential on the second circuit, the other diode having its anode connected to a point of relatively low alternating potential on the second circuit, a resistive impedance connecting the 15 cathodes of said diodes, means establishing a point of said second circuit intermediate said two points at the potential of the high alternating potential side of the first circuit, means establishing an intermediate point of said impedance at said first intermediate point potential, means for utilizing direct current voltage developed across said impedance by the rectification action of the diodes, said last means comprising a network provided with a frequency 20 determining circuit, and a direct current voltage connection being connected between one end of the impedance and said frequency determining circuit for frequency adjustment of the latter.

18. In combination with a resonant circuit 25 tuned to a desired wave frequency, a second resonant circuit tuned to the same frequency, said circuits being loosely coupled, a source of waves coupled to the first circuit, a pair of diode rectifiers, one of the diodes having its anode connected to the high alternating potential side of the second circuit, the other diode having its anode connected to the low alternating potential side of the second circuit, a resistor connecting the cathodes of said diodes, one end of the resistor being at ground potential, means establishing the mid-point of said second circuit at the potential of the high alternating potential 30 side of the first circuit, means connecting the mid-point of said resistor to said first mid-point, and a direct current voltage path connected to the ungrounded end of the resistor for utilizing direct current voltage developed across the resistor by the rectification action of the diodes.
